PENCIL SHARPENER

Jack Fairchild Fleming, Summit, N.J., assignor to Sterling Plastics Co., Mountainside, N.J., a corporation of New Jersey

Filed Apr. 15, 1964, Ser. No. 79,502

Term of patent 14 years

(Cl. D74—21)

Fig. 1

Fig. 3

Fig. 2

FIG. 1 is a perspective view of a pencil sharpener embodying my new design;

FIG. 2 is an end elevational view thereof looking in the direction of the arrows 2—2 on FIG. 1; and

FIG. 3 is a side elevational view thereof looking in the direction of the arrows 3—3 on FIG. 1.

I claim:

The ornamental design for a pencil sharpener, substantially as shown.
